UNITED STATES PATENT OFFICE.

ELISHA WILLIAM BABCOCK, OF LORAIN, OHIO, ASSIGNOR OF ONE-HALF TO JOHN E. KITCHEN, OF LORAIN, OHIO.

ARTIFICIAL LEG.

1,259,588.

Specification of Letters Patent. Patented Mar. 19, 1918.

Application filed August 31, 1917. Serial No. 189,118.

To all whom it may concern:

Be it known that I, ELISHA W. BABCOCK, a citizen of the United States, residing at Lorain, in the county of Lorain and State of Ohio, have invented certain new and useful Improvements in Artificial Legs, of which the following is a specification.

This invention relates to artificial limbs of the character shown in my Patent No. 1,232,173, and has for its object to simplify and improve the construction shown in such patent.

With the foregoing objects in view that will more fully appear as the nature of the invention is better understood, the same consists in the novel features of construction, combination and arrangement of parts illustrated in the drawings and more particularly pointed out in the appended claim.

20 In the accompanying drawings:—

Figure 1 is a vertical longitudinal section of an artificial limb embodying my improvements;

Fig. 2 is a bottom plan view of Fig. 1;

25 Fig. 3 is an edge view of the upper foot plate;

Fig. 4 is a similar view of the toe clip;

Fig. 5 is a detail perspective view of the heel cushion;

30 Fig. 6 is a similar view of the heel cushion; and

Fig. 7 is a perspective view illustrating the operation of the invention.

Referring to the drawings for a more particular description of the invention and which drawings are for illustrative purposes only, and are therefore not drawn to scale, 1 designates the stump socket which is preferably formed of wood and the lower portion

40 2 of which forms the instep of the foot. Secured to the bottom of the instep 2 is a foot plate 3 which is held in place by a series of two or more rivets 4 which extend preferably at an angle through the upper

45 foot member or instep 2 with their upper and lower ends countersunk in the latter and the foot plate 3, respectively. The foot plate 3 aforesaid is also secured in place by the vertical bolt 5, which passes upwardly

50 through corresponding openings in the rear end of said foot plate and the heel portion of the foot member 2 with its upper threaded end 6 projecting into the socket 7 of the stump 1. A washer 8 is arranged on the upper threaded end of the bolt 5 against

the bottom wall 9 of the socket 7 and provides a bearing for the lock nut 10, as shown in Fig. 1 of the drawings.

The numeral 11 represents the sole member which is formed at its rear end with a heel portion 12 and is provided at its front end with an upturned tubular portion or sleeve 13 which, as shown in Fig. 2 of the drawings, is of less length than the width of the sole, thereby leaving the side spaces 14. The device further comprises a flat toe clip 15 which is provided at its rear end and opposite side edges with the upturned eyes 16 which register with corresponding eyes 17 formed at the front end of the foot plate 3 through which eyes, and the tubular portion 13 of the sole member 11, passes the connecting pin 18.

A toe piece 19 is secured to and upon the toe clip 15 by the vertical rivets 20 or other equivalent means. It will be observed by reference more particularly to Figs. 1 and 5 of the drawings, that the toe piece 19, which is formed of rubber or other material possessing the desired resiliency, is formed with a recess 21 to receive the eyes 16 and 17, and the tubular portion or sleeve 13 of the sole member 11. The eyes 17 of the foot plate are provided with the outwardly curved extensions or fingers 22 which fit and work against the upper rear wall or edge 23 of the toe piece 19, the purpose of which will be hereinafter set forth. A heel cushion 24 is arranged in the heel portion 12 of the sole member 11 upon the top of which rests 25 and works the rear end of the foot plate 3. The upper inner edge of the heel cushion 24 is provided with a recess 25 to accommodate the head 26 of the bolt 5. The rear wall 27 of the heel portion 12 of the sole member 11 is provided with a vertical slot 28 which receives a lug 29 formed on the rear end of the foot plate 3, whereby the vertical or up and down movement of the foot plate is held within predetermined limits.

100

By providing a toe piece 19 and a heel cushion 24, I am able to dispense with the springs shown in my patent issued July 13, 1917, No. 1,232,173. It will also be observed that the toe piece provides the desired resiliency or elasticity at the toe of the foot while the heel cushion 24 provides the desired spring or cushioning effect at the heel, when walking. This construction is not only more dependable and economical in

105

110

construction, but greatly simplifies the invention and renders it of more utility through the opportunity thereby afforded to dispense with a number of the parts.

5 From the foregoing description taken in connection with the drawings, it is thought that the construction, operation and advantages of this invention will be readily understood without requiring a more extended explanation.

10 Various changes in the form, proportions and minor details of construction may be resorted to without departing from the principles or sacrificing any of the advantages 15 of this invention as defined in the appended claim.

Having described my invention, what I claim as new and desire to secure by Letters Patent, is:—

20 An artificial limb comprising a stump socket, the lower portion of which forms the instep of the foot, an upper foot plate secured to the bottom of the instep and provided at its front end with a pair of upturned eyes formed with vertically disposed

25 lugs or fingers, a sole member disposed beneath said upper foot plate and provided at its front end with an upturned tubular portion or sleeve registering with said eyes, a toe clip having eyes registering with those of the upper foot plate, a cross pin passing through the eyes of the toe clip and the upper foot plate and the tubular portion or sleeve of the sole member for hingedly connecting the aforesaid parts together, a solid resilient toe member secured to the toe clip with its upper inner wall or edge working against the lugs or fingers of the upper foot plate, and a solid heel cushion arranged in the sole member and providing a resilient support for the heel portion of the upper foot plate, and means for limiting the vertical or up-and-down movement of said foot plate.

30 In testimony whereof I affix my signature in the presence of two witnesses.

ELISHA WILLIAM BABCOCK.
